UNITED STATES PATENT OFFICE.

WILLIAM H. DAY, OF EAST HAVEN, CONNECTICUT, ASSIGNOR, BY MESNE ASSIGNMENTS, TO REMINGTON RAND INC., OF TONAWANDA, NEW YORK, A CORPORATION OF DELAWARE.

INDEX OR FILE.

Application filed April 21, 1925. Serial No. 24,765.

This invention relates to index devices of the class in which a series of index cards or reference members are arranged upon a carrying frame or in a drawer or similar supporting device in such a manner that a portion of each is exposed to view, one above the other, to facilitate ready reference thereto, the exposed portion being adapted to bear information regarding the nature of the data upon the remaining portion of the card. More particularly the invention relates to a retainer designed for application to a reference member or card and adapted to removably support another card or the like thereon.

It is often desirable in devices of this character that card holders be provided with means whereby a card may be detachably mounted upon the same so that a margin of the card will be exposed to view when so mounted, and the holders are arranged in overlapped relation. Various card holders have been provided for obtaining this result, some having transparent pockets along one margin by which additional cards are supported and others having means such as clips at an upper margin for gripping the added card. This invention contemplates an improvement over card holders of these types and provides a card holder wherein index cards already in use in so-called box indexes, as well as cards not having been so used, may be mounted upon the card holder in a simple and inexpensive manner without the disadvantage of causing a bulky thick edge at either margin of the holder, which is usually found in these types of holders due to the thickness of the overlapped materials forming the pockets or the like at the margins thereof.

One of the objects of this invention, therefore, is to generally improve card holders of this type so that the cards mounted thereon may be readily referred to, easily attached and detached therefrom.

Another object of this invention is the provision of a card or reference member holder, having means to retain a card thereon, which will be inexpensive, efficient in use and which decreases to a minimum the thickness of the combined holder and insert at the free edge thereof.

Another object of this invention is to provide card-retaining means of such a form and construction that the same may be

readily applied to a reference member of the hinged type, thereby adapting said member to removably retain another reference member or card upon the flap portion thereof in such a manner that the side edges 60 and one marginal edge of both will coincide.

Other objects of this invention which are improvements in devices of this character will appear as the same is hereinafter described and claimed.

In the accompanying drawings:

Fig. 1 illustrates a supporting frame having a plurality of card holders mounted thereon, which embody the features of this 70 invention;

Fig. 2 is a section on line 2—2 of Fig. 1;

Fig. 3 is an enlarged plan view of the free margin of one of the card holders, with a corner of the superposed card broken 75 away;

Fig. 4 is an enlarged rear view of the card holder shown in Fig. 3;

Fig. 5 is an enlarged side view of the free marginal portion of one of the card 80 holders;

Fig. 6 is a section through a corner of a card holder, looking in the direction of arrow 6—6 of Fig. 3;

Fig. 7 is a section across a corner of a 85 card holder, looking in the direction of arrows 7—7 of Fig. 3;

Fig. 8 is a detailed perspective of the superimposed card-supporting member used in connection with my improved card holder, 90 and

Fig. 9 is a section on line 9—9 of Fig. 1.

A plurality of index reference members or card holders 10, embodying the features of my invention, are shown mounted upon a 95 suitable support 11 in Fig. 1. These holders are arranged to overlap each other a predetermined amount so that a portion of each may be exposed to view, as shown at 19. The support 11 may be a shallow 100 drawer or may be a leaf or frame as illustrated. The card holders 10 are illustrated as being composed of two portions 12 and 13, 12 being the base portion and 13 the flap portion. These portions are hingedly connected at 14 in any suitable manner, such as a weakened line, a connecting strip of flexible fabric, or as shown, by a series of spaced hinged members 15 formed by a series of perforations. The base portion 12 is pro- 110

vided with a pair of integral tongues 16 which engage a retaining strip 17 mounted in or on the support 11. The construction and cooperation between the tongues 16 and the retaining strip 17 is fully described in the patent to Irving Fisher, No. 1,048,056 dated December 24, 1912.

A reference member supporting means 23 is secured at each corner of the free edge 10 of the flap portion 13 of each card holder. The supporting means 23 is preferably a thin ribbon-like strip of resilient material, and in this instance, is composed of a strip of metal 23', see dotted lines in Fig. 8, and is preformed before being secured at the corner of a card, as shown in full lines. The member 23 comprises a base or front plate portion 24, card edge engaging portions 25 and 26, arm or wing portions 27 and 28 parallel to each other and extending perpendicularly relatively to the front plate portion 24, and card-engaging pointed end portions 29 and 30 extending vertically upward from each of the arm portions.

25 When assembled upon a card holder, the portion 24 extends diagonally across the upper surface of the same, and is slightly spaced upwardly therefrom, the portions 25 and 26, respectively, being without and 30 against the marginal and side edges of the card holder. The arm portions 27 and 28 extend along the under surface of the same, and the pointed ends 29 and 30 extend through the material and are bent over the 35 upper surface thereof. As illustrated, the pointed ends 29 and 30 are threaded through preformed openings 32 and 33, respectively, provided in the card holder, but where the material of the card holder is thin the pointed ends 29 and 30 would readily puncture the material and can be inserted therethrough. It is preferable that the ends 29 and 30 be pressed downwardly into close 40 contact with the material of the card holder, even to the extent of being forced into the same, and that the bend is in a direction toward the diagonally disposed portion 24, so that these ends will not interfere with the insertion of the superposed card 31 but will 45 present a substantially smooth rounded edge at the bend.

Because of extending to and over the edges of the flap 13 at each side of the corner portion thereof, the member 23 allows the superimposed card or insert 31 to be of the same width as the flap portion 13, and to extend to the free edge of the same. The side edges of the superimposed card or insert 31, therefore, will coincide with the side edges of the flap portion 13, and the bottom or marginal edge of the insert 31 will coincide with the free or marginal edge of the flap portion 13, thereby completely covering the lower portion of the flap.

In some instances, the clamping effect of the member 23 upon the corner of the inserted card caused by the resiliency of the material from which the member is made, is sufficient to hold the insert 31 upon the 70 flap portion 13, but in other instances, it is desirable to use instrumentalities for engaging the upper margin of the insert to insure that the same will be properly retained on the holder. For this purpose, 75 tongues 20 and 21 are illustrated in the drawings and are located adjacent the hinge connection 14, being struck from the material of the card holder and joined thereto at 22.

As shown in Fig. 9, the connecting portion 22 of these tongues allows the tongues to rest flatwise upon the surface of the insert or card 31. Insert-engaging means or tongues are therefore provided which, in their entirety are out of the plane of the card holder body yet parallel thereto. This feature obviates the tendency for the tongues to catch upon adjacent cards or other articles because of lying flatwise upon the insert, while engaging the same, instead of extending at an angle away from the surface of the insert, which disadvantage was usually found in indexes of this type previous to this invention. Preferably 90 the tongues 20 and 21 are spaced from the plane of the card holder an amount substantially equal to the thickness of the material thereof.

The above described card holder is obviously capable of being used as a record-bearing member, either separately or when an insert is mounted thereon and when provided with a readily applied insert or additional card clamping and retaining means, such as the member 23, is also capable of supporting index cards upon a surface thereof. The advantages obtained in the use of the above described holder are largely due to the form and the arrangement thereon of the member 23, in combination with a reference member of the type illustrated, and in some instances, with such a reference member wherein the novel integral tongues 20 and 21 are provided.

The supporting means 23 may, of course, be furnished as a separate part to card index owners and users, so that the existing reference members may be adapted to support additional cards thereon and thereby become card holders. This is readily accomplished by securing the preformed corner member 23 shown in Fig. 8 upon the index cards of a series at present in use, and will not destroy the usefulness of the original index.

While I have illustrated and described a preferred form of the device embodying my invention, I do not limit myself to the exact details shown, as many modifications

and variations thereof are possible which will lie within the spirit of the invention and the scope of the appended claims.

What I claim is:

5. 1. In an index or file, a pair of reference members in superimposed relation with the side edges and a marginal edge of one coinciding with the corresponding edges of the other, and means secured to one adapted to 60
10 detachably retain the other thereon, said means comprising a preformed ribbon-like member.
2. In an index or file, a pair of reference members in superimposed relation with the side edges and a marginal edge of one coinciding with the corresponding edges of the other, and means secured to and extending 65
15 across the corners adjacent the margin of one member and beyond said marginal edge and the adjacent edges thereof, comprising a preformed ribbon-like member for detachably retaining the other reference member thereon.
3. In an index or file, a pair of reference members in superimposed relation with the side edges and a marginal edge of one coinciding with the corresponding edges of the other, and means secured to one adapted to 70
20 detachably retain the other thereon, said means comprising a preformed ribbon-like member, and means adjacent the other margin of one of the reference members for engaging the opposite edge of the other reference member.
35. 4. A reference member for an index or file, having card-holding means secured thereon whereby said reference member is capable of detachably supporting a card, said means comprising a member having a portion 75
40 thereof extending across a corner of said reference member and beyond the adjacent edges and over a surface thereof, the ends of said member extending through said reference member and being bent over the surface 80
45 of said member in a direction toward and perpendicular to the portion extending across the corner of said reference member.
5. In an index or file, a card-retaining member adapted to embrace the corners of 85
50 two superposed cards to secure them together, said member being preformed from ribbon-like resilient material and having a portion adapted to extend diagonally across the corners of the cards, a portion at each 90
55 end of the diagonally extending portion adapted to extend vertically therefrom across the edges of the cards, and a portion 95
60 adapted to extend over the opposite surface of the cards, and means associated with the last-mentioned portion adapted to engage 65
65 one of the cards to retain said member in position thereon.
6. In an index or file, a member preformed of ribbon-like material and adapted to be applied to a card for securing another card thereto, said member comprising a base portion having vertically depending portions at each end thereof bent diagonally thereto, other portions bent diagonally with respect 70
75 to each of the depending portions and disposed perpendicularly in relation to the base portion, and means on the last-named portions whereby said member may be secured to a card.
7. A preformed member of ribbon-like 80
85 springable material, adapted to be applied at the corner of a card for securing another card thereto, comprising a base portion having an arm portion extending perpendicularly from each end thereof, pointed end portions extending substantially vertically to said arm portion, and means connecting said arm portions to said base portions, each comprising a portion vertical to and diagonally disposed in respect to said arm portions and said base portion.
8. Means for retaining two card-like members together, comprising a strip of ribbon-like material having a portion adapted to lie flatwise upon a surface of one of the members, portions bent diagonally to and vertically depending from said first-mentioned portion at the ends thereof, whereby said portions are substantially at right angles to each other, other portions bent diagonally to 90
95 and vertically outward from said depending portions, said last-mentioned portions being adapted to lie flatwise upon a surface of the other of said members, and means associated with each of said last-mentioned portions to 100
105 secure said retaining means to said other member.
9. A new article of manufacture, comprising a strip of material preformed to present a front plate having an arm at each end thereof, said arms extending from said plate at right angles thereto and parallel to each other as and for the purpose described, each of said arms having a pointed end extending vertically upward therefrom as and for the purpose described.

In witness whereof, I have hereunto set my hand this 15 day of April, 1925.

WILLIAM H. DAY.

CERTIFICATE OF CORRECTION.

Patent No. 1,667,539.

Granted April 24, 1928, to

WILLIAM H. DAY.

It is hereby certified that error appears in the printed specification of the above numbered patent requiring correction as follows: Page 2, line 70, before the word "upon" insert the word "firmly"; and that the said Letters Patent should be read with this correction therein that the same may conform to the record of the case in the Patent Office.

Signed and sealed this 29th day of May, A. D. 1928.

(Seal)

M. J. Moore,
Acting Commissioner of Patents.
